HINGED LID BOX

Joseph Kramer, Reading, Ohio, assignor to The Gardner Board and Carton Co., Middletown, Ohio, a corporation of Ohio

Application October 6, 1955, Serial No. 538,959

11 Claims. (Cl. 229—36)

My invention has to do with hinged lid boxes and more particularly to the provision of hinged lid boxes having improved corner locking means and improved means for maintaining the bottom and lid parts together once the structure has been erected and closed.

Hinged lid boxes of the character contemplated herein are in widespread use in the suit box and kindred fields and are preferred by the retailer in that they may be stored in the form of flat blanks which require a minimum of storage space and readily assembled in the shipping or wrapping room as needed. Considerable difficulty has, however, been experienced with this type of box in that the parts, once assembled, have a tendency to come apart at the corner interlocks, particularly if the filled box is dropped or subjected to rough handling during delivery. Efforts have been made to overcome these difficulties by tying or taping the boxes; but these expedients are both time consuming and add to the cost of the package.

It is, therefore, a principal object of my invention to provide an improved hinged lid box in which the corners, once they have been assembled, cannot be accidentally disengaged, and in which the cover of the box, when closed over the bottom, is positively secured to the bottom along three sides thereof.

A further object of my invention is the provision of a hinged lid box in which the side and rear walls of the box are reinforced by extensions formed as integral parts of the one-piece box blank.

These as well as other objects of my invention which will appear hereinafter or which will be apparent to the skilled worker in the art upon reading these specifications, I accomplish by those constructions and arrangements of parts of which I shall now describe certain exemplary embodiments.

Figure 1 is a plan view of a box blank in accordance with my invention.

Figure 2 is an enlarged fragmentary plan view illustrating tongue receiving cuts in the front wall of the box bottom.

Figure 2a is a plan view similar to Figure 1 illustrating a modified form of tongue receiving cuts.

Figure 3 is a partial perspective view illustrating the walls of the box bottom in an intermediate stage of erection.

Figure 4 is a fragmentary perspective view illustrating the manner in which one of the corner locks of the box is formed.

Figure 5 is a perspective view similar to Figure 3 illustrating the corner locks in fully assembled position.

Figure 6 is a perspective view of the assembled box with the cover in partly closed position.

Figure 7 is a perspective view illustrating the box lid of Figure 6 in the fully closed position.

Figure 8 is a plan view of a box blank incorporating integrally formed side and rear wall reinforcing means.

Figure 9 is a plan view of the blank of Figure 8 with the reinforcing parts in initially folded position.

2

Figure 10 is a partial perspective view illustrating the blank of Figure 9 in partly assembled condition.

Figure 11 is a perspective view illustrating the box of Figure 10 in fully assembled position with the cover partially open.

Figure 12 is a perspective view of the completely erected and closed box.

Figure 13 is a vertical sectional view taken along the line 13—13 of Figure 12.

10 As seen in Figure 1, I have illustrated a blank for a hinged lid box formed from paperboard or boxboard suitably cut and scored to provide integral bottom and cover parts. The blank provides a bottom part having a main panel 1, side panels 2 and 3 articulated to opposite sides thereof, and a front panel 4 articulated to the front edge of the main panel. The corner portions at the ends of the front and side walls are divided into two parts by the diagonal score lines 5 extending outwardly from the corners of the main panel 1 partially through the corner portions and contacted at their outer ends by the angularly related lines of cut 6 which extend outwardly to the free edges of the corner portions opposite the ends of the side panels, thereby dividing the portions into inner bellows folding parts 7 articulated to the ends of the front panel 4 and outer bellows folding and locking parts 8 articulated to the ends of the side panels, the latter parts having oppositely directed tongue portions 9 and 10. The tongue portions 9 are defined by the lines of cut 6 and the adjacent outer edges of the corner portions and are 30 of generally triangular configuration. The tongue portions 10 lie at the outer corner edges of the corner portions and are of generally rectangular configuration, being separated from the body of the parts 8 by the score lines 11.

35 The front panel 4 is provided near each end with configured slit portions 12 and 13 which are adapted, as the structure is assembled, to receive the tongue portions 9 and 10. As best seen in Figure 2, the slit portion 12, which receives the tongue portion 9, is of what may be termed "ear-shaped" configuration, having a curved intermediate segment terminating at its ends in reversely curved segments 14 and 15, the slit thus defining an irregular tab 16. The slit portion 13 also has reversely turned end segments 17 and 18 which define a tab 19. 45 Alternatively, as seen in Figure 2a, the slit portions 12 and 13 may be joined together in a continuous irregular slit by connecting together the reversely turned segments 14 and 18 of the two slit portions.

45 Referring again to Figure 1, the remainder of the box blank comprises a rear wall 20, a lid forming panel 21 having side flanges 22 and 23 articulated to opposite side edges thereof and a front flange 24 articulated to its remaining edge. Diagonally scored connecting webs 25 lie at the ends of the rear wall 20 and serve to interconnect the adjacent end edges of the side panels 2 and 3 to the side flanges 22 and 23, respectively, of the cover part.

55 In order to tightly secure the bottom and cover parts together in erected and closed condition, the front flange 24 is provided with spaced apart recessed tongues 26 and 27 adapted to be engaged through the generally U-shaped slits 28 and 29 formed in the front panel 4. Similarly, the side flanges 22 and 23 are provided with recessed tongues 30 and 31 adapted to be engaged through the slits 32 and 33 in the side panels 2 and 3 of the bottom part, the slits 32 and 33 being similar in configuration to the slits 28 and 29.

65 In erecting and assembling the blank just described, the side panels 2 and 3 and the front panel 4 of the bottom part are first erected in the manner illustrated in Figure 3, thereby juxtaposing the inner and outer bellows folding parts 7 and 8, the bellows folding parts extending outwardly beyond the front panel 4, whereupon the bel-

lows folding parts are folded inwardly. As the parts are folded inwardly the bottom, inclined edges of the triangular tongue portions 9 are inserted through the slit portions 12, in the manner illustrated in Figure 4, the bottom edges of the tongues sliding along the intermediate portions of the slits as they are inserted, followed by the infolding of the tongue portions 10 and their insertion through the slot portions 13. The insertion of the tongue portions through the slit portions 12 and 13 is facilitated by the inward flexing of the tabs 16 and 19 of the slits. The assembled front and side panels are illustrated in Figure 5 of the drawings wherein it will be seen that the tongue portions are securely engaged in the slits and hence locked in place. The natural resiliency of the tabs 16 and 19 acts to maintain the tongue portions in the engaged position and prevents them from being readily withdrawn. In addition, it is also within the spirit of my invention to provide the tongue portion 9 with notches 34, as seen in Figure 5, which engage about the edges of the slit portions 12, thereby providing an additional point of locking engagement.

The cover may be closed down over the box bottom by folding the diagonally scored connecting webs 25 inwardly in the manner seen in Figure 6, whereupon the lid forming panel 21 is moved downwardly with the side flanges 22 and 23 lying to the outside of the side panels 2 and 3, and the front flange 24 lying to the outside of the front panel 4. As the side and front flanges are brought into overlapping relation with the corresponding panels of the bottom part, the recessed tongues, which preferably have rounded ends as illustrated, are passed through the corresponding slits in the panels, thereby bringing the parts to the assembled condition illustrated in Figure 7. It will be noted that the configuration of the slits 28, 29, 32 and 33 is such that they have generally S shaped end segments which interlock with the rounded ends of the recessed tongues. When in the closed position, it will be seen that all three sides of the cover part are positively secured to the bottom part. This not only prevents the bottom and cover parts from becoming disengaged but, in addition, prevents flexing or bending movement of the side and front panels independently of the corresponding cover flanges, thereby strengthening and rigidifying the structure. With respect to the front flange 24, it will be noted that this flange overlies and covers the exposed areas of outer bellows folding and locking parts 8 and provides additional assurance that the tongue portions 9 and 10 will not be accidentally disengaged from the slit portions. The two spaced apart tongues 26 and 27 assist in this function since they are placed adjacent the tongue portions 8 and 9 and hence tend to prevent flexing of the adjacent portions of the front flange 24.

It has been found that a hinged lid box constructed in the manner described is extremely sturdy and may be dropped and otherwise roughly handled without the parts becoming disengaged. At the same time the construction of the box is such that no more material is required than in a conventional hinged lid box, nor does the structure require the use of string, tape or the like to secure it together.

In Figure 8, I have illustrated a modified form of my invention incorporating integral reinforcing parts for the side and rear walls of the box. Since the basic box construction is identical with that disclosed hereinbefore, like parts have been given like reference numerals in the remaining figures of the drawings.

As seen in Figure 8, side panel extensions 40 and 41 are articulated to the free side edges of side panels 2 and 3, respectively, the extensions having cut away portions 42 and 43 in the areas thereof which overlie the configured slits 32 and 33. Reinforcing straps 44 and 45 extend rearwardly from the end edges of the extensions 40 and 41, the straps lying adjacent but separated from the connecting webs 25 and the side flanges 22 and 23 of the

cover. At their ends the straps are provided with oppositely directed pairs of slits 46, 47 and 48, 49.

As an incident to the formation of the box blank, the extensions 40 and 41 and the straps 44 and 45 will be infolded in the manner illustrated in Figure 9 and the extensions 40 and 41 only will be adhesively secured to the underlying side panels 2 and 3, as by means of adhesive areas 49 (Figure 8) previously applied to the upper surfaces of the side panels 2 and 3. Alternatively, the adhesive could be applied to the exposed upper surfaces of the extensions 40 and 41, if so desired. The straps 44 and 45 remain free from attachment to the underlying flanges 22 and 23.

Successive stages in the erection and closing of the blank just described are illustrated in Figures 10-12 of the drawings. Upon erection of the front and side panels of the bottom part and interengagement of the tongue portions, the straps, as seen in Figure 10, will be swung across the box and the oppositely directed slits interengaged to secure the straps together in the manner best seen in Figure 11. Thus the box structure has reinforced double thickness side panels and a triple thickness rear wall. This provides an extremely sturdy, easily secured and heavily reinforced hinged lid box which requires only a minor addition to the amount of boxboard required to form the box blank. Since the reinforcing straps are engaged across the rear wall of the box as an incident of its erection, the use of special box making equipment is avoided, as conventional folding and gluing equipment may be used for the folding of the extensions.

Modifications may, of course, be made in my invention without departing from the spirit of it. Having thus described my invention in certain exemplary embodiments, what I desire to secure and protect by Letters Patent is:

1. In a hinged lid box including a main panel, front and side panels, a rear wall, and a cover connected to said rear wall, corner connecting members joining the ends of the front and side panels, said corner connecting members each being divided by a diagonal score line and an angularly related line of cut into an inner bellows folding part articulated to said front panel and an outer bellows folding and locking part articulated to the adjacent side panel, said last named bellows folding and locking part including a pair of oppositely directed tongue portions, the parts of said corner connecting members being adapted to be folded to overlie said front panel, and slit portions in said front panel adjacent the ends thereof for receiving the tongue portions of said locking parts.

2. In a hinged lid box having a bottom part including a main panel, front and side panels, a rear wall, and a cover connected to said rear wall, said cover including front and side flanges, corner connecting members joining the ends of said front and side panels, said corner connecting members each being divided by a diagonal score line and an angularly related line of cut into an inner bellows folding part articulated to said front panel and an outer bellows folding and locking part articulated to the adjacent side panel, said last named locking part including a pair of oppositely directed tongue portions, said corner connecting members being adapted to be folded to overlie said front panel, slit portions in said front panel adjacent the ends thereof for receiving said tongue portions, recessed locking tongues formed in the front and side flanges of said cover, and mating tongue receiving slits in the front and side panels of said bottom part for receiving said last named locking tongues.

3. In a hinged lid box including a main panel, front and side panels, a rear wall, and a cover connected to said rear wall, corner connecting members joining the ends of the front and side panels, said corner connecting members each being divided by a diagonal score line and an angularly related line of cut into an inner bellows folding part articulated to said front panel and an outer bellows folding and locking part articulated to the adjacent side

panel, said last named locking part including a pair of oppositely directed tongue portions, extensions articulated to the free side edges of said side panels, and strap members connected to the end edges of said extensions adjacent said rear wall, said corner connecting members being adapted to be folded to overlie said front panel, slit portions in said front panel for receiving the tongue portions of said locking parts, said extension lying in infolded condition and adhesively secured to the underlying side panels, said strap members being adapted to be folded across the rear of said box in juxtaposed relation, and means for joining together the juxtaposed strap members.

4. In a hinged lid box including a main panel, front and side panels, a rear wall, and a cover connected to said rear wall, corner connecting members joining the ends of the front and side panels, said corner connecting members each being divided by a diagonal score line and an angularly related line of cut into an inner bellows folding part articulated to said front panel and an outer bellows folding and locking part articulated to the adjacent side panel, said last named locking part including a pair of oppositely directed tongue portions, extensions articulated to the free side edges of said side panels, and strap members connected to the end edges of said extensions adjacent said rear wall, said corner connecting members being adapted to be folded to overlie said front panel, slit portions in said front panel for receiving the tongue portions of said locking parts, recessed locking tongues formed in the front and side flanges of said cover, and mating tongue receiving slits in the front and side panels of said bottom part for receiving said last named locking tongues, said extensions lying in infolded condition and adhesively secured to the underlying side panels, said strap members, in the erected box, being adapted to be folded across the rear of the box in juxtaposed relation, and means for joining together the juxtaposed strap members.

5. In a collapsible box having a main panel and front and side panels connected to said main panel, corner connecting members joining the ends of said front and side panels, said corner members each being divided by a diagonal score line and an angularly related line of cut into an inner bellows folding part articulated to said front panel and an outer bellows folding and locking part articulated to the adjacent side panel, said last named

locking part including a pair of oppositely directed tongue portions, the parts of said corner connecting members being adapted to be folded to overlie said front panel, and slit portions in said front panel adjacent the ends thereof for receiving the tongue portions of said locking parts.

6. The structure claimed in claim 5 wherein said score line extends outwardly from the adjacent corner of the main panel partially through the corner member and is contacted at its outer end by the angularly related line of cut, the said line of cut extending outwardly from the end of said score line to the free edge of the corner member opposite the end of the side panel to which said corner member is connected.

15 7. The structure claimed in claim 6 wherein a first of said oppositely directed tongue portions is defined by the said line of cut and the adjacent outer edge of the corner connecting member, and wherein the other of said tongue portions lies at the outer corner edge of the said corner member.

20 8. The structure claimed in claim 7 wherein said first named tongue portion is of generally triangular configuration, and wherein the other of said tongue portions is of generally rectangular configuration and is separated from 25 the body of said locking part by means of a score line.

9. The structure claimed in claim 8 wherein the slit portion for receiving the said triangular tongue portion is of ear-shaped configuration, and wherein the slit portion for receiving the other of said tongue portions lies in 30 spaced relation to said first named ear-shaped slit portion.

10. The structure claimed in claim 8 wherein the slit portion for receiving said triangular tongue portion is of ear-shaped configuration, and wherein the slit portion for receiving the other of said tongue portions is formed 35 as an integral extension of said ear-shaped slit portion.

11. The structure claimed in claim 10 wherein said triangular tab portions include notches at the point of juncture between said diagonal score line and said angularly related line of cut.
